United States Patent Office

Des. 228,749
Patented Oct. 23, 1973

228,749

VEHICLE TRAILER

Malte Swensson, Los Angeles, Calif. (10741 Moorpark St., Apt. 30, North Hollywood, Calif. 91602)

Filed Dec. 20, 1971, Ser. No. 210,313

Term of patent 14 years

Int. Cl. D12—10

U.S. Cl. D14—3 E

F-2-9.3F-2-9.4F-2-9.5FIG. 1 is a perspective view of a vehicle trailer, showing my new design;

FIG. 2 is a top plan view thereof;

FIG. 3 is a right side elevational view thereof;

FIG. 4 is a left side elevational view thereof; and

FIG. 5 is a rear elevational view thereof.

I claim:

The ornamental design for a vehicle trailer, substantially as shown.
